UNITED STATES PATENT OFFICE

BEN D. BARTON, OF BATTLE CREEK, MICHIGAN, ASSIGNOR TO AMERICAN STEAM PUMP COMPANY, OF BATTLE CREEK, MICHIGAN, A CORPORATION OF MICHIGAN

POWER ATTACHMENT FOR MOTOR VEHICLES

Original No. 1,482,880, dated February 5, 1924, Serial No. 600,460, filed November 11, 1922. Application for reissue filed January 11, 1926. Serial No. 80,677.

This invention relates to improvements in power attachments for motor vehicles.

The main objects of this invention are:

First, to provide an improved power attachment for motor vehicles, which may be readily mounted upon a vehicle.

Second, to provide an improved power attachment for motor vehicles in which the parts are so arranged that the strain or pull of the driving belt is largely carried or sustained by the attachment, thereby avoiding the racking of the vehicle to which the attachment is applied.

Third, to provide an improved power attachment for motor vehicles which enables a direct drive from the driving shaft of the motor.

Fourth, to provide an improved power attachment for vehicles in which the parts are formed and arranged so that they may be knocked down or disassembled for convenience in transportation and handling.

Objects pertaining to details and economies of construction and operation will definitely appear from the detailed description to follow.

I accomplish the objects of my invention by the devices and means described in the following specification. The invention is clearly defined and pointed out in the claims.

A structure which is a preferred embodiment of my invention is clearly illustrated in the accompanying drawing forming a part of this application, in which:

Figure I is a front perspective view of my improved power attachment shown in operative position upon a motor vehicle of well known type, parts of the outline of the vehicle being indicated by dotted lines.

Figure II is a detail view partly in vertical longitudinal section, on a line corresponding to line 2—2 of Figures I, V and VI.

Figure III is a similar fragmentary sectional view with the driving pulley supporting frame removed.

Figure IV is a fragmentary plan view partially in section to better illustrate structural details.

Figure V is a fragmentary front elevation with the driving pulley supporting frame removed.

Figure VI is a detail section on a line corresponding to line 6—6 of Figure II.

Figure VII is a detail section on a line corresponding to line 7—7 of Figures I and VI showing details of the frame and the manner of assembling and disassembling the same.

In the drawings the sectional views are taken looking in the direction of the little arrows at the ends of the section lines and similar reference characters refer to similar parts throughout the several views.

Referring to the drawing, 1 represents a cross member of the chassis frame and 2 the front spring thereof. The engine body is represented at 3 (see Figure II) and the driving member or shaft at 4. In practice I remove the fan belt pulley with which the machine is usually equipped and substitute the fan belt pulley 5 having a forwardly projecting sleeve-like hub 6 terminating in the jaw clutch member 7. I also substitute a plate-like bracket 8 for a bracket usually employed to support the forward end of the cranking spindle, the cranking spindle being also removed. The bracket 8 has a flat face and an inwardly projecting arm-like portion which rests upon the frame member 1 and is clamped thereto by U-bolts as illustrated, the bracket projecting upwardly above the frame member as shown in Figure V.

The bracket 8 is provided with holes 9 and 10 adapted to receive attaching bolts 11 of the pulley supporting frame 12 so that this pulley supporting frame is detachably secured to the bracket 8, it being intended that the bracket 8 shall remain in place and the supporting frame 12 being attached or removed as may be desired.

The frame 12 is provided with a bearing 13

for the spindle 14 of the driving pulley 15. This spindle or driven member is disposed longitudinally of the vehicle and in alignment with the driving shaft 4. The spindle is provided with a jaw clutch member 16 at its inner end.

Intermediate the driving shaft 4 and driven member 14 is a shaft section 17 forming part of the driving connection between the driving and driven members. This shaft section 17 is provided with a clutch member 18 connecting with clutch member 7 and with a clutch member 19 coacting with the clutch member 16. This shaft 17 is a floating shaft; that is, it is mounted for axial movement being held yieldingly outward by the coiled spring 20 arranged in the hub or sleeve 6 to disengage the clutch member 7 and 18 and being held with all of the clutch members in engagement 20 when the pulley supporting frame is mounted on the bracket as shown in Figure II.

The bracket 8 is provided with a conical or outwardly tapered opening 21 while the clutch member 19 has a conical periphery 25 adapted to engage this tapered opening when the frame 12 is removed, thereby preventing rattling of the parts.

I provide a pair of idler pulleys 22 which are carried by the shaft 23 supported above 30 and transversely to the driving pulley by means of the uprights 24 and the braces 25. These uprights rest in seats 26 provided therefor in the arms 27 of the supporting frame 12, the arms being provided with pins 35 28 adapted to engage holes 29 in the lower ends of the uprights, the uprights being engageable and disengageable with a tilting and swinging movement. This prevents the uprights jarring off the arms.

40 At the upper ends of the uprights are bearings 30 for the shaft 23. The braces 25 terminate in boxes 31 adapted to receive the ends of the shaft. The inner ends of the braces 25 are engaged with hooks or projections 25' on the chassis frame. The bearings 30 have forwardly projecting arms 32 carrying the upright guide pulleys 33. The guide disk 34 is disposed between the pulleys with its tapered periphery projecting beyond the same. This guide disk is freely rotatable in either direction.

The spindle of the pulley 15 is provided with a cross pin 35 with which a suitable crank may be engaged for cranking the engine 55 should that be desired or necessary. The same crank is also designed to be engaged with the clutch member 19 when the power mechanism is removed. The engine 3 is provided with a forwardly projecting hanger member 3' which is engaged with the supporting bracket 8, see Figures II and III, so that the supporting bracket performs the double function of supporting the driven part and also of an engine hanger support.

65 With this arrangement of parts the power

mechanism may be quickly and easily applied to the motor vehicle or automobile and in operation there is little stress upon the parts. The belt 36 is supported and guided to very effectively deliver the power.

70

I have illustrated and described my invention in an embodiment which I have found very practical and as I have adapted the same for automobiles or pleasure vehicles, I have not attempted to illustrate and describe my improvements with such modifications as might be necessary or desirable for attaching them to trucks and tractors as I believe the disclosures made will enable those skilled in the art to which my invention relates to embody or adapt the same as may be desired.

75

What I claim is:

1. The combination in a structure of the class described, of a chassis, a driving shaft 85 mounted on the chassis; a supporting bracket secured to said chassis and having an opening therein; an axially movable shaft section interposed between the driving shaft and said bracket, interengaging clutch members 90 on said shaft section and driving shaft, a spring for yieldingly holding said shaft section in clutch disengaging position, and a member on the outer end of said shaft section having a tapered fit in the opening in 95 said bracket when the clutch is disengaged.

2. The combination in a structure of the class described, of a chassis, a driving shaft mounted on the chassis; a supporting bracket secured to the chassis and having an opening, 100 a supporting frame detachably attached to said bracket, a driven member mounted on said supporting frame, a clutch to connect said shaft and driven member, an axially movable shaft section interposed between the 105 driving shaft and driven member; clutch members on the shaft section adapted to engage the clutch members on said driving shaft and driven members; a spring for yieldingly holding said shaft section in clutch disengaging position; the clutch member at the outer end of said shaft section having a tapered fit in the opening in said bracket when the 110 clutches are disengaged.

115

3. The combination in a structure of the class described, of a chassis, a driving shaft mounted on the chassis; a supporting bracket secured to said chassis and having an opening therein; a supporting frame detachably attached to said bracket; a spindle mounted 120 on said supporting frame; clutch members on said shaft and spindle, an axially movable shaft section interposed between the driving shaft and spindle; clutch members on said shaft section coacting with the clutch members on said driving shaft and spindle, said clutch members being held in engagement when said supporting frame is mounted on said bracket, and a spring for yieldingly holding said shaft section in its clutch dis- 125 130

- engaging position when said pulley supporting frame is removed, the clutch member at the outer end of said shaft section having a tapered fit in the opening in said bracket when the clutches are disengaged.
4. The combination in a structure of the class described, of a chassis frame, a supporting bracket mounted on said frame, a pulley supporting frame detachably secured to said bracket, a driving pulley mounted on said pulley supporting frame, a driving shaft, a clutch connection for said shaft and driving pulley, an idler pulley shaft disposed above and transversely of said driving pulley, and supports for said idler shaft detachably connected with said chassis frame.
5. The combination in a structure of the class described, of a chassis frame, a supporting bracket mounted on said frame, a pulley supporting frame having a longitudinally disposed bearing detachably mounted on said bracket, a spindle disposed in said bearing, a driving shaft, a clutch connection for said shaft and spindle comprising jaw clutch members on said shaft and spindle and an axially movable clutch member shaft having jaw clutch members thereon coacting with the clutch members of said driving shaft and spindle, the clutch members being held in engagement when said pulley supporting frame is mounted on said bracket, and a spring for yieldingly holding said clutch member shaft in its clutch disengaging position when said pulley supporting frame is removed.
6. The combination in a structure of the class described, of a chassis frame provided with a front cross member, a supporting bracket secured to said front cross member, a pulley supporting frame having a longitudinally disposed pulley spindle bearing detachably mounted on said bracket, a driving pulley provided with a spindle disposed in said bearing, a driving shaft, a clutch connection for said shaft and spindle comprising jaw clutch members on said shaft and spindle and an axially movable clutch member shaft having jaw clutch members thereon coacting with the clutch members of said driving shaft and spindle, the clutch members being held in engagement when said pulley supporting frame is mounted on said bracket, and a spring for yieldingly holding said clutch member shaft in its clutch disengaging position when said pulley supporting frame is removed.
7. The combination in a structure of the class described, of a chassis frame provided with a front cross member, a supporting bracket secured to said front cross member, a supporting frame having a longitudinally disposed spindle bearing detachably mounted on said bracket, a spindle disposed in said bearing, a driving shaft mounted on the chassis, a pulley secured to said driving shaft and having an outwardly projecting sleeve-like hub provided with a clutch member, an axially movable shaft disposed with its inner end slideable in said hub and provided with a clutch member coacting with the clutch member on said hub, a spring disposed in said hub adapted to normally disengage said clutch members, a clutch member on said pulley spindle, and a clutch member on said axially movable shaft coacting therewith, said clutch members being held in engagement when the supporting frame is mounted on said bracket.
8. The combination in a structure of the class described, of a chassis frame provided with a front cross member, a supporting bracket secured to said front cross member and having an outwardly tapered opening therein, a pulley supporting frame having a longitudinally disposed pulley spindle bearing detachably mounted on said bracket, a driving pulley provided with a spindle disposed in said bearing, a driving shaft, a clutch connection for said shaft and spindle comprising jaw clutch members on said shaft and spindle and an axially movable clutch member shaft having jaw clutch members thereon coacting with the clutch members of said driving shaft and spindle, the clutch members being held in engagement when said pulley supporting frame is mounted on said bracket, and a spring for yieldingly holding said clutch member shaft in its clutch disengaging position when said pulley supporting frame is removed, the clutch member at the outer end of said clutch member shaft having a conical periphery engaging said tapered opening in said bracket when the clutches are disengaged.
9. The combination in a structure of the class described, of a chassis frame, a supporting bracket mounted on said frame and having an outwardly tapered opening therein, a pulley supporting frame having a longitudinally disposed pulley spindle bearing detachably mounted on said bracket, a spindle disposed in said bearing, a driving shaft, a clutch connection for said shaft and spindle comprising jaw clutch members on said shaft and spindle, and an axially movable clutch member shaft having clutch members thereon coacting with the clutch members of said driving shaft and spindle, the clutch members being held in engagement when said supporting frame is mounted on said bracket, and a spring for yieldingly holding said clutch member shaft in its clutch disengaging position when said pulley supporting frame is removed, the clutch member at the outer end of said clutch member shaft having a conical periphery engaging said tapered opening in said bracket when the clutches are disengaged.
10. The combination in a structure of the class described, of a chassis frame provided with a front cross member, a supporting bracket secured to said front cross member

- and having an outwardly tapered opening therein, a supporting frame having a longitudinally disposed spindle bearing detachably mounted on said bracket, a spindle disposed in said bearing, a driving shaft mounted on the chassis frame, a fan belt pulley secured to said driving shaft and having an outwardly projecting hub provided with a clutch member, an axially movable shaft disposed with its inner end slidably in said hub and provided with a clutch member co-acting with the clutch member on said hub, a spring disposed to normally disengage said clutch members, a clutch member on said spindle, and a clutch member on said axially movable shaft coacting therewith, said clutch members being held in engagement when the pulley supporting frame is mounted on said bracket, the clutch member at the outer end of said axially movable shaft having a conical periphery which is held in engagement with said tapered opening in said bracket when the pulley supporting frame is removed.
11. The combination in a structure of the class described, of a chassis frame, a supporting bracket mounted on said frame, a pulley supporting frame having laterally projecting arms detachably secured to said bracket, a driving pulley carried by said pulley supporting frame, an idler shaft disposed above and transversely of said driving pulley, idler shaft supporting uprights detachably engaged with said arms and having bearings for said idler shaft, and braces connecting said idler shaft to said chassis frame.
12. The combination in a structure of the class described, of a chassis frame, a supporting bracket mounted on said frame, a pulley supporting frame having laterally projecting arms detachably secured to said bracket, a driving pulley carried by said pulley supporting frame, an idler shaft disposed above and transversely of said driving pulley, and idler shaft supporting uprights detachably engaged with said arms and having bearings for said idler shaft.
13. The combination in a structure of the class described, of a chassis frame provided with a front cross member, a supporting bracket secured to said front cross member, a pulley supporting frame having a longitudinally disposed pulley spindle bearing detachably secured to said bracket, a driving pulley provided with a spindle disposed in said bearing, a driving shaft, a clutch connection for said shaft and spindle comprising jaw clutch members on said shaft and spindle and an axially movable clutch member shaft having jaw clutch members thereon coacting with the clutch members of said driving shaft and spindle, the clutch members being held in engagement when said pulley supporting frame is mounted on said bracket, a spring for yieldingly holding said clutch member shaft in its clutch disengaging position when said pulley supporting frame is removed, idler pulleys, means carried by said pulley-supporting frame and chassis frame for supporting said idler pulleys.
14. In a power attachment of the character described the combination with a chassis and a driving shaft mounted thereon, of a supporting bracket mounted on said chassis, a supporting frame detachably mounted on said bracket, a rotatable driven member mounted on said supporting frame but not axially movable with respect thereto, a driving connection including a shaft section between said driving shaft and said driven member, engaged with the driving shaft and driven shaft by the act of mounting the supporting frame on the bracket, and means for automatically disengaging said shaft section from the driving shaft, said disengaging means being put into operation by the act of disengaging the driven member from the shaft section.
15. In a power attachment of the character described, the combination with a chassis and a driving shaft mounted thereon, of a supporting bracket mounted on said chassis, a supporting frame detachably mounted on said bracket, a driven member on said supporting frame, a driving connection including a shaft section between said driving shaft and said driven member, and means for holding the outer end of said shaft section in engagement with the bracket when the said supporting frame is detached.
16. In a power attachment of the character described, the combination with a chassis and a driving shaft mounted thereon, of a supporting bracket mounted on said chassis, a supporting frame on said bracket, a driven member on said supporting frame, a shaft section operatively connected at one end to the driving shaft, means for connecting the other end of said shaft section with said driven member, said connecting means operating through an opening in said bracket and being rendered operative by the act of attaching said frame to said bracket and inoperative when the supporting frame is removed, and means for automatically disengaging said shaft section from the driving shaft when the driven member is disengaged therefrom.
17. The combination in a structure of the class described, of a chassis frame provided with a front cross member, a supporting bracket secured to said front cross member, a supporting frame detachably secured to said bracket, a spindle journaled in said supporting frame, a driving shaft mounted on the chassis, clutch members on said shaft and spindle, an axially movable shaft section intermediate the driving shaft and spindle, clutch members on the shaft section co-acting

with the opposed clutch members on said driving shaft and spindle the connection between shaft section and spindle being established through an opening in said bracket; the 5 clutch members being adapted to be held in engagement when said supporting frame is mounted on said bracket; and a spring for yieldingly holding said shaft section disengaged from the driving shaft when said 10 supporting frame is removed.
